CLAIM

The ornamental design for a matt board corner sample, as shown and described.

DESCRIPTION

FIG. 1 is a top left perspective of the matt board corner sample;

FIG. 2 is a front elevation, the bottom plan view being identical, of the matt board corner sample;

FIG. 3 is a rear elevation, the top plan view being identical, of the matt board corner sample; and,

FIG. 4 is a right side elevation, the left side being a mirror image thereof, of the matt board corner sample.
